UNITED STATES PATENT OFFICE.

EDWIN BERTRAM PIKE, OF PIKE, NEW HAMPSHIRE.

COMBINED WHETSTONE, BLOTTER, AND PAPER-WEIGHT.

No. 824,138.

Specification of Letters Patent.

Patented June 26, 1906.

Application filed November 6, 1905. Serial No. 235,985.

To all whom it may concern:

Be it known that I, EDWIN BERTRAM PIKE, a citizen of the United States, residing at Pike, in the county of Grafton, State of New Hampshire, have invented a new and useful Improvement in a Combined Whetstone, Blotter, and Paper-Weight; and I do hereby declare that the following is a full, clear, and exact description of the same.

10 My invention relates to a new article of manufacture which can be conveniently used as a whetstone for sharpening knives and other edged tools, as a blotter, and as a paper-weight, and is also well adapted for advertising purposes.

The invention consists, briefly, of a whetstone, acting also as a handle and a weight secured upon a blotting-pad, substantially as hereinafter described and claimed.

20 Reference is to be had to the accompanying drawings, forming part of this specification, in which like numbers designate corresponding parts in both figures.

Figure 1 is a plan view of a combined whetstone, blotter, and paper-weight embodying my invention. Fig. 2 is a cross-sectional view of the same.

In the drawings, 10 is a whetstone of preferably circular form which is secured upon 30 a metal or other stiff cover 11, pressing upon a blotting-pad 12, also by preference of circular form, so that the whetstone will have a steady base and will conveniently serve for sharpening knives and other edged implements. The whetstone will also serve 35 as a convenient handle for manipulating the blotting-pad 12, and by its weight and that of the cover 11 superimposed upon said blotting-pad it will serve in combination therewith as a very simple and efficient paper-weight.

The blotting-pad 12 is by preference composed of a number of superimposed sheets of blotting-paper secured together by means of a fastener 13, passing through several 45 sheets.

In a central recess 14 in the under side of the whetstone 10 is secured a headed screw 15, which is fitted to screw detachably into a nut 16, secured upon the top of the blotting-pad 12, so that when the under sheet of blotting-paper is used up it can be easily removed and a fresh sheet uncovered for use, and when all the blotting-sheets are used a new pad may be easily substituted. 55

The upper side of the cover 11 may, as shown, be overlaid with a label 17 for advertisements, &c.

Having thus set forth the nature of my invention and the manner in which I carry 60 the same into practice, I claim as my invention—

1. The combination, with a pad of superimposed flat blotting-sheets, a fastener passing through the superimposed blotting-sheets, a stiff cover secured on top of said blotting-pad, and a combined whetstone, weight and handle secured upon said stiff cover, substantially as described. 65

2. The combination, with a whetstone and 70 a stiff cover secured to the under side thereof, of a screw fitted to the whetstone and a blotting-pad having a nut fixed thereon into which the screw is fitted detachably, substantially as described. 75

In testimony whereof I have hereunto set my hand this 31st day of July, 1905.

E. BERTRAM PIKE.

In presence of—

H. C. BROWN,
E. BLANK.
